UNITED STATES PATENT OFFICE

140,115

DESIGN FOR A POWDER COMPACT

Willard E. Gerbing, Park Ridge, Ill.

Application October 11, 1944, Serial No. 115,712

Term of patent 3½ years

(Cl. D86—10)

To all whom it may concern:

Be it known that I, Willard E. Gerbing, a citizen of the United States, residing at Park Ridge, in the county of Cook and State of Illinois, have invented a new, original, and ornamental Design for a Powder Compact, of which the following is a specification, reference being had to the accompanying drawing, forming part thereof.

Figure 1 is a plan view of a powder compact embodying my new design;

Figure 2 is a side view of the powder compact; and

Figure 3 is a central sectional view of the powder compact.

I claim:

The ornamental design for a powder compact, as shown.

WILLARD E. GERBING.
